US00D704544S

(12) **United States Design Patent**
Oetlinger

(10) **Patent No.:** **US D704,544 S**
(45) **Date of Patent:** **** May 13, 2014**

(54) **NUT**

(71) Applicant: **Blanking Systems, Inc.**, Grafton, WI (US)

JP 2004-060789 2/2004
KR 10-02155558 8/1998

(72) Inventor: **Frank E. Oetlinger**, Grafton, WI (US)

(Continued)

(73) Assignee: **Blanking Systems, Inc.**, Grafton, WI (US)

Primary Examiner — Cynthia Underwood

(***) Term: **14 Years**

(74) *Attorney, Agent, or Firm* — Boyle Fredrickson, S.C.

(21) Appl. No.: **29/448,396**

(22) Filed: **Mar. 12, 2013**

Related U.S. Application Data

(63) Continuation-in-part of application No. 13/273,988, filed on Oct. 14, 2011.

CLAIM

The ornamental design for a nut, as shown and described.

(51) **LOC (10) Cl.** **08-08**

DESCRIPTION

(52) **U.S. Cl.**

FIG. 1 is an isometric view of a first embodiment of a nut in accordance with the present invention;

(58) **Field of Classification Search**

FIG. 2 is an end view of the nut of FIG. 1;

USPC **D8/397**
USPC D8/397, 394, 382, 349, 356, 399, 363,
D8/352; 403/291, 309, 300, 301, 310, 311,
403/403, 331, 387; 411/427, 429, 432, 918,
411/180, 81, 337; D25/119; 2/897

FIG. 3 is a top plan view of the nut of FIG. 1;

See application file for complete search history.

FIG. 4 is a bottom plan view of the nut of FIG. 1;

(56) **References Cited**

FIG. 5 is a side elevational view of a first side of the nut of FIG. 1;

U.S. PATENT DOCUMENTS

FIG. 6 is a side elevational view of a second side of the nut of FIG. 1;

42,320 A * 4/1864 Thomas 470/87
2,809,686 A * 10/1957 Shepherd 411/104
3,066,773 A 12/1962 Raidel
3,456,413 A 7/1969 Fischer
3,901,612 A 8/1975 Canin

FIG. 7 is an isometric view of a second embodiment of a nut in accordance with the present invention;

(Continued)

FIG. 8 is an end view of the nut of FIG. 7;

FIG. 9 is a top plan view of the nut of FIG. 7;

FIG. 10 is a bottom plan view of the nut of FIG. 7;

FIG. 11 is a side elevational view of a first side of the nut of FIG. 7; and,

FIG. 12 is a side elevational view of a second side of the nut of FIG. 7.

The broken lines are included for illustrative purposes only and form no part of the claim. The broken away symbols in the drawings indicate that any portion of the article beyond that which is shown forms no part of the claimed design.
